UNITED STATES PATENT OFFICE.

GUY L. PITTS, OF ROCKY MOUNT, NORTH CAROLINA.

DESIGN FOR A ROAD SIGN.

Application filed January 21, 1928. Serial No. 24,965. Term of patent 14 years.

To all whom it may concern:

Be it known that I, GUY L. PITTS, a citizen of the United States, residing at Rocky Mount, in the county of Edgecombe and State of North Carolina, have invented a new, original, and ornamental Design for a Road Sign, of which the following is a specification, reference being had to the ac-

companying drawing, forming part thereof.

The figure is a view in perspective of a road sign embodying my design.

I claim:—

The ornamental design for a road sign, as shown.

GUY L. PITTS.
